KNITTING MACHINE

Edgar J. Martel, Laconia, N. H.

Application November 5, 1932, Serial No. 641,371

20 Claims.

(Cl. 66—51)

This invention relates to knitting machines of the circular type adapted to knit tubular objects such as seamless hosiery. The ordinary seamless stocking is ill-fitting since the angle portion 5 thereof is not small enough in comparison with the top portion to fit snugly about the ankle. It is an object of this invention to provide a circular knitting machine which is capable of fashioning, that is, which can knit tubular work with an increasing or decreasing number of wales. To this end, I provide a machine such that the circumference of the needle cylinder thereof, as well as the number of active needles therein, may be increased or decreased during the operation of the machine. As hereinafter described in detail, I provide a two-part needle cylinder, the parts of which are hinged together and are adapted to overlap.

For a more complete understanding of the invention, reference may be had to the following description of an embodiment thereof, and to the drawings, of which,

Figure 1 is a sectional view of a portion of a knitting machine embodying the invention, certain parts being omitted to avoid confusion of detail.

Figure 2 is a plan view of the machine partly illustrated in Figure 1.

Figure 3 is a section on the line 3—3 of Figure 1.

Figure 4 is a section on the line 4—4 of Figure 1.

Figure 5 is a section on the line 5—5 of Figure 1.

Figure 6 is an elevation of a stitching cam.

Figure 7 is a section on the line 7—7 of Figure 1.

Figure 8 is an elevation of a post showing cam

35 actuators mounted thereon.

Figure 9 is a perspective view of a portion of Figure 8 showing the cam actuator mechanism in more detail.

Figure 10 is an elevation of the needle cylinder 40 and certain other portions of the apparatus associated therewith, this view being taken on the line 10—10 of Figure 1.

Figure 11 is a fragmentary view of a portion of the apparatus as indicated by the line 11—11 of 45 Figure 10.

Figures 12, 13, 14 and 15 are fragmentary sectional views of the overlapping portions of the cylinders, the several figures showing the parts in different relative positions.

50 Figure 16 is a perspective view of portions of the needle cylinders and mechanism for moving certain of the needles into and out of operative position.

Figure 17 is a fragmentary plan view of the 55 overlapping portions of the sinker holding rings and sinkers.

Figure 18 is a fragmentary plan view similar to 60 Figure 17, some of the parts being in different positions of operation.

Figure 19 is a section on the line 19—19 of Figure 18.

Figure 20 is a sectional view similar to Figure 19 showing parts in different positions.

Figure 21 is a fragmentary elevation of the mechanism shown in Figure 18.

Figures 22 to 29, inclusive, illustrate various successive positions of a needle and the loop changer in the step of transferring a loop from one needle to the next needle in fashioning.

Figure 30 illustrates a fragment of a knitted fabric which can be made on the machine illustrated.

Figure 31 illustrates a fashioned stocking 15 which can be knit by a machine embodying the invention.

As the invention relates to improvements in knitting machines of the circular type, embodiments of the invention may take the form of structural additions to and changes in the standard circular knitting machines known and used in the art. Hence, in the embodiment illustrated on the drawings, portions only of a standard knitting machine are shown, many other portions such as are customarily parts of such machines being omitted to avoid confusion of detail.

According to the invention, a machine of the circular type is so constructed that the effective circumference of the needle cylinder can be increased or diminished, needles 30 being put into or out of action in accordance with the change in circumference. As shown in Figure 1, the machine may comprise a stationary bed or frame, a portion of which is indicated at 40. A horizontal gear wheel 41 is supported by 35 this frame and is driven by any suitable driving means through a gear wheel 42 meshing therewith. The needle cylinder, instead of being the customary unitary hollow cylinder, is made in two parts, according to the present invention, one 40 part 45 being approximately semi-cylindrical, the other part 46 being approximately semi-conical.

The semi-cylindrical portion of the needle cylinder is hereinafter referred to as the long cylinder, the other portion of the needle cylinder being referred to for convenience as the short cylinder. Each of these cylinders is provided with external milled slots in which the knitting needles are 45 slidably mounted, long needles 47 being mounted in the long cylinder 45, shorter needles 48 being 50 mounted in the short cylinder 46. The long cylinder is supported by suitable pins 50 which extend through holes in the gear wheel 41 and rest on a ball bearing member 51. The ball bearing member 51 in turn rests upon a cylinder tube 52 55 which is vertically adjustable in the bed plate 40 so that the needle cylinder is also vertically adjustable. The short cylinder 46 is supported by the long cylinder 45, these cylinders being hinged 60 together as by a hinge pin 55 extending through

5 a pair of brackets 56 and 57 secured respectively to the long and short cylinders. As shown in Figure 5 the portions of the long and short cylinders remote from the hinge are adapted to overlap, the long and short cylinders being relatively swingable on the hinge to increase or diminish the amount of overlap within defined limits. In the embodiment of the invention illustrated, the long cylinder does not swing toward or from its axis of rotation for varying the overlap, such 10 adjustive movement being confined to the short cylinder. Mechanism for varying the overlap is provided, such mechanism comprising a flat semi-ring 60 which is secured to the bracket 56, and a similar semi-ring 61 above the semi-ring 60, the semi-ring 61 being secured to and supported by the short cylinder 46 as by suitable bracket 62. On the portions of the semi-rings 60 and 61 remote from the hinge are mounted 15 guide members 65, 66 (Figures 1 and 3) to maintain the long and short cylinders in their proper relation to each other. Near the guide members 65 and 66 on the semi-rings 60 and 61 are a pair of racks 67 and 68, these racks facing each other so that a pinion 70 may ride between them and mesh with both of them. The pinion 70 is mounted on a short shaft 71 which is supported by a ring 72 immediately above the semi-ring 61. The ring 72 is free to move about a vertical pin 20 73 which is mounted in the bracket 56. On the outer end of the shaft 71 is mounted a star wheel 75, rotation of which results in the changing of the overlap of the long and short cylinders. The star wheel 75 and the pinion 70 are so designed that rotation of the star wheel through an angle from one tooth to the next swings the short cylinder 46 about the pivot 55 through an angle corresponding to the spacing between successive needles in the cylinder. Thus the needles 25 in the overlapping portion of the cylinder are always radially aligned with the needles in the overlapped portion of the long cylinder 45. As indicated in Figures 1 and 5, the upper portion of the cylinder is tapered so that the tops of the 30 needles in the overlapping portion thereof are approximately in the circular line of circumference defined by the needles of the long cylinder. Thus the needles of the long and short cylinders are positioned to take the yarn from the same 35 yarn feeders and to operate together like the needles in the cylinder of an ordinary circular knitting machine. For the operation of the star wheel 75 to open or close the needle cylinder, a pair of stationary arms may be provided, one 40 of these arms 76 being at a level to engage the upper portion of the star wheel 75 to open the cylinder (Figure 1) the other arm 77 being adapted to engage the lower portion of the star wheel 75 to close the cylinder. These arms are mounted 45 on a stationary post 80 and are selectively movable into the path of the star wheel 75 by any suitable means such as a cam element 82 having cam faces 85 adapted to engage cam faces 86 on the arm 76 and 77, the movement of this cam 50 element being preferably controlled by a suitable cam drum (not shown) such as is customarily found on circular knitting machines. Spaced from the post 80 on either side thereof are a pair of posts 81 and 83 which carry cam-actuating 55 arms hereinafter described. It is evident that if the cam member 82 is pushed upwardly from an intermediate position in which neither arm is advanced inwardly, the cam surfaces will move the arm 76 into the path of the uppermost spoke 60 of the wheel 75 as indicated in Fig. 1. The low-

ering of the cam member 82 below its intermediate position will move the arm 77 into operative position in the path of the lowermost spoke of the wheel 75. The arms 76 and 77 as well as other equivalent arms for similar purposes, may 5 be operated by such or equivalent mechanism.

Whenever the cylinder is increased in circumference, it is necessary to add needles one at a time to the circle of operating needles. When the cylinder is to be reduced in circumference, it is necessary to drop needles out of action one at a time prior to each telescoping movement of the cylinder. Mechanism for moving needles in the overlapping portions of the long and short cylinders into and out of operative position is 10 illustrated in Figures 1, 10 and 16. In addition to the customary butt 90 for engagement with stitching cams, each of the needles 47 and 48 in the overlapping and overlapped portions of the 15 cylinders may be provided with a pair of butts 91 and 92 adapted for engagement by strikers 95 and 96. The striker 95 is adapted to strike the butt 91 of a needle from below to raise the needle into operative position. This takes place immediately after an opening movement of the 20 cylinder. The striker 96 is adapted to strike the butt 92 of an operative needle from below to raise the needle sufficiently for the removal of its loop of yarn, as is hereinafter described, then to strike the butt 91 of the same needle from 25 above to move the needle down and out of operative position. This takes place immediately prior to a closing movement of the cylinder. As shown in Figure 16 the striker 95 may be provided with two lugs 100 and 101 projecting toward the cylinder for direct engagement with the butts of long-cylinder needles and short-cylinder needles 30 respectively, the angular relation of the lugs 100 and 101 about the axis of the cylinder being such that when either is positioned for engagement 35 with an adjacent needle butt, the other is offset between two needles so that movement of the striker 95 results in the engagement of a needle of either the short cylinder or the long cylinder, but not both simultaneously. In like manner the 40 striker 96 has a pair of lugs 102 and 103 which are similarly arranged with respect to the needles of the long and short cylinders respectively. Any suitable means for operating the strikers 95 and 96 may be provided. As shown, the strikers 95 50 and 96 are rockably mounted on a support bracket 105 which in turn is carried by a block 106 slideable in a dovetail groove in a bracket 107 secured to the short cylinder 46. A bracket 108 is secured to the long cylinder 45, these two brackets 107 55 and 108 having thereon opposing racks 110 and 111, respectively. A pinion 112 is in mesh with both of the racks and is rotatably supported by the block 106. As a result of this construction, opening and closing movement of the short cylinder 46 relative to the long cylinder 45 results in movement of the rack 110 relative to the rack 111. The pinion 112 between these racks also moves along the rack 111, its distance of motion being half that of the rack 110. Hence the lateral movement 60 of the bracket 105 is half that of the short cylinder 46, that is, about half the spacing between successive needles for each step of movement.

Mechanism may be provided as illustrated in Figure 16 for operating the strikers 95 and 96. As shown, a gear sector 115 is rockably mounted on the lower portion of the bracket 105 for operating the striker 95 when a needle is to be raised into operative position. A pinion 116 meshes with 75

the gear sector 115 and is loosely mounted on a shaft 117. A ratchet element 120 is mounted on the shaft 117 and is engaged by a pawl 121 carried by the pinion 116. The shaft 117 also carries a crank arm 122 which is connected as by a rod 123 to the striker 95. A single rotation of the shaft 117 from the position shown in Figure 16 causes the lugs 100 and 101 of the striker 95 to rise for a predetermined distance, then descend for a greater distance, then return to the original position shown. Such rotation of the shaft 117 is produced by a rocking movement of the gear sector 115, this gear sector having an arm 130 projecting radially therefrom with a cam member 131 secured thereto. The cam member 131 has a sloping cam surface 132 adapted to engage an arm 135 supported by the post 81. This cam engaging arm is somewhat similar to the arm 11 and is movable in or out by a member 136 controlled by a suitable cam on the cam drum hereinbefore referred to, and working against a spring 137 which bears against the outer end of the arm 135. When the arm 135 is projected into the path of the cam member 131, it rides on the cam surface 132 as the member 131 passes. This results in an upward swing of the gear sector 115 and a reciprocation of the striker 95 with its lugs 100 and 101, one of the latter being in line with a needle butt 91 so as to raise the needle into operative position. In like manner a similar cam member 140 with a cam surface 141 to engage an arm 142 on the post 83 is provided for the actuation of the striker 96, this cam member 140 being operatively connected to the striker 96 as by a supporting arm 145 secured to a gear sector 146 which meshes with a pinion 147 loosely mounted on a shaft 150. A ratchet member 151 is mounted on a shaft 150 and is engaged by a pawl 152 secured to the pinion 147. The rotation of the shaft 150 causes rocking movement of the striker 96 by reason of a connection consisting of the crank arm 153 and pitman 154. When the gear sector 146 is swung upwardly by the engagement of the cam member 140 with the arm 142, the shaft 150 is rotated through a single revolution, this rotation causing the lugs 102 and 103 of the striker 96 to rise above their normal position, then to descend below their normal position, then to return to normal position. Thus the lug 102 (or 103) first engages the needle butt 92 which is in line therewith and raises the needle sufficiently for the removal of its loop, as hereinafter described. The needle is then lowered by the engagement of the lug with the butt 91. This lowering motion of the needle is sufficient to put it completely out of action until it is subsequently raised by engagement of the lug 100 or 101 with the butt 91.

The machine is provided with sinkers 160, these sinkers being radially slidable in a sinker retaining ring which is composed of two separate semi-rings 165 and 166 so that the circle of sinkers can be varied in circumference together with the needle cylinder. To this end the semi-ring 165 may be supported on the semi-ring 60 as by a suitable standard 167. In like manner the semi-ring 166 may be supported on the semi-ring 61 as by a standard 168. The standards 167 and 168 also carry a split ring 170 to guide a pair of sinker cam brackets 171 and 172, as shown in Figure 1. These brackets may be resiliently mounted on poles of the stationary frame, the bracket 171 being mounted on an upright frame member 175, the bracket 172 being carried by the post 80. Each of the brackets 171 and 172 may consist of

a yoke, the lower arm of which engages the guide ring 170. Of the yoke 171 the upper arm is provided with a cam member 176 adapted to be engaged by lugs 177 on the sinkers. In like manner the upper arm of the yoke 172 carries a cam member 178 engageable by the lugs 177 of the sinkers. A spring or other elastic element 180 is employed to press against the outer ends of the sinkers on each semi-ring to press the sinkers inwardly. In the overlapping portions of the sinker rings the sinkers are so shaped and arranged that some of them can be moved into or out of operative position with an increase or decrease in the size of the cylinder. As indicated in Figure 10, the overlapped portion 181 of the semi-ring 165 extends under the overlapping portion of the semi-ring 166. Figure 20 illustrates a pair of sinkers in the overlapping ring portions in which the lower sinker 185 in the ring portion 181 is in its inoperative position beneath an upper sinker 186 in the semi-ring 166. When the cylinder is given an opening movement, one of the lower sinkers 185 is moved laterally clear of the end of the semi-ring 166 and is then ready to be raised into its operative position as shown in Figure 19. Each sinker 185 is provided with suitable slots 187 through which extends a pair of pins 188 and 189. These pins are mounted in the overlapped portion 181 of the semi-ring 165. The sinker 185 may be moved from its inoperative position into an operative position as by a claw 191 on a lever 192 pivoted as at 193 on a bracket 194. The claw 191 engages the projection 195 on the sinker 185 to push the sinker upwardly and into operative position. A second claw 196 is carried by the lever arm 192 in such a way as to engage the projection 195 to move the sinker 185 back to inoperative position. For the operation of the lever arm 192, a cam member 200 is mounted thereon, this member having a lower sloping cam edge 201 adapted to ride on a stationary arm 204, and an upper cam edge 203 adapted to ride on a stationary arm 202. The arm 202 is carried by the post 81, the arm 204 being carried by the post 83. These arms are provided with devices for selectively moving them in or out of the path of motion of the cam member 200, the movement of the arms 202 and 204 being controlled by the cam drum hereinbefore referred to.

It is evident that during the normal operation of the knitting machine, when the needle cylinder is in its closed or telescoped position, the sinkers in the overlapping portions of the sinker retaining rings will ride in slots in the upper edges of both the long and short cylinders. These sinkers must be retracted sufficiently from the cylinders to permit relative movement thereof and to be clear of adjacent needles before the short cylinder is moved in either direction relative to the long cylinder. To this end the cam 178 is so shaped, as shown in Figure 17, that all the sinkers are retracted in turn as they pass the location where the overlapping portions of the cylinder must be at the moment when the short cylinder is given an opening or closing movement. The other sinker cam 176 fulfills the usual function of retracting the sinkers adjacent to needles which are stitching.

When the cylinder is being closed so as to reduce its circumference, a needle must be lowered to inoperative position immediately before each step of the closing movement. It is also necessary that the loop which is carried by such needle be transferred to an adjacent needle so as to com-

- bine the two wales of the fabric into a single wale. To this end I may provide a loop changer 210 radially slideable in a member 211 which is positioned immediately above the needle cylinder so that the member 211 and the needle cylinder maintain a substantially constant angular relation. The member 211 is secured to a sleeve 212 on which is mounted a gear wheel 213 (Figure 2). 5
- 10 This gear wheel 213 is geared by an idle gear wheel 214 to a pinion 215 mounted on the upper end of a shaft 216 which may extend down through the hollow post 80 to be driven by a suitable connection (not shown) with the gear wheel 41. This 15 train of gearing is such as to rotate the needle cylinder and the member 211 in the same direction and at the same speed. Nesting within the sleeve 212 is an inner sleeve 220 which is axially movable and also rotates with the sleeve 212 at 20 the same rate as the needle cylinder. Projecting from the lower end of the sleeve 220 is a hollow arm 221 having a slanting cam slot 222 in the end thereof (Figure 10). The loop changer 210 is provided with a finger 223 projecting through 25 the slot 222. This finger is normally at the mid point of the slot 222 so that when the sleeve 220 is raised or lowered, the loop changer 210 is swung laterally to one side or the other through the arc subtended by the group of needles from which 30 loops are to be taken. Thus a loop taken from one needle may be moved over to the adjacent needle on either side as desired. In order to take a loop from a needle, it is necessary to project the loop changer 210 radially. To this end, it is provided at its rear end with a sloping cam face 225 engageable by the bevelled lower end of a rod 226 which is slidably fitted within the sleeve 220 for axial movement therein, but which is rotatable with the sleeve 220 and the sleeve 212. Suitable 35 mechanism may be provided for controlling the up and down movement of the sleeve 220 and the rod 226. Downward movement of the rod 226 results in outward movement of the loop changer against the tension of a spring band 227 which 40 passes around the front of the loop changer. For the actuation of the sleeve 220 an arm 230 (Figure 2) may be provided with a fork to engage collars 229 on the sleeve 220 so that the sleeve may be raised and lowered by the rocking of the arm 230 45 without interfering with the rotation of the sleeve. In like manner an arm 231 may engage collars on the rod 226 for similar purposes, the arms 230 and 231 being rockably mounted on a standard 232 rising from a bracket 233 at the upper end of the standard 175. Connecting links 235, 236 may 50 be attached to the other ends of the arms 230 and 231 to rock the arms, the links 235 and 236 being connected by well known devices to a cam drum (not shown) for the control of the movements of the loop changer 210. The relative movements of 55 the loop changer 210 and a needle 47 in the process of removing a loop from the needle and transferring it to an adjacent needle, are illustrated in Figures 22 to 29. When a needle is to be lowered 60 out of action preparatory to a closing movement of the cylinder, the needle is first elevated by the projection 102 or 103 of the striker 95 or 96 until it reaches a position such as that shown in Figure 22, the loop slipping below the latch of the needle. 65 The loop changer 210 is then moved radially outward by actuation of the rod 226 to the position shown in Figure 24, the tip 238 of the loop changer picking up the loop as it passes the needle as 70 shown in Figure 23. Meanwhile the needle is being lowered by the projection 102 or 103, the 75

loop slipping over the latch and clear of the needle so that it is held in a notch 239 in the tip of the loop changer. This downward movement of the needle continues until the needle is out of operative position, that is, low enough to avoid engagement with its stitching cam. The loop changer 210, holding the loop in the notch 239, is now shogged or swung laterally by a vertical movement of the cam member 221. The projection 223 of the loop changer rides in a diagonal slot 222 of this cam member so that vertical movement of the latter results in a lateral swing on the part of the loop changer in one direction or another from an inclined position. Thus the loop from the needle 47 can be shifted to the adjacent needle on either side of the needle from which the loop has been taken. When the loop changer has been thus shogged, it takes a position relative to the adjacent needle as shown in Figure 26. When this needle reaches its stitching cam it is elevated to a position to take the yarn from the 20 yarn feeder. During its rising movement the loop changer remains stationary until the hook of the needle has passed through the loop held by the notch 239 of the loop changer, as shown in 25 Figure 27. The loop changer is then retracted radially as the needle rises further, this being illustrated in Figure 28. When the needle is elevated sufficiently to take the yarn from the 30 yarn feeder, its original loop and the added loop which it has received from the loop changer both slip below the open latch as shown in Figure 29. The needle now takes the fresh yarn and descends to form a new loop, casting off both of the old loops together. The resulting fabric is illustrated 35 in Figure 30, this fabric showing the result of knitting with successive closing movement of the cylinder in successive revolutions of the cylinder during the narrowing process. Four steps of narrowing are illustrated in Figure 30 but it is understood that more or fewer narrowing steps may be taken, and that these steps need not be taken in successive courses but may be spaced by one or more courses of plain knitting.

In widening a fabric by opening movement of 45 the cylinder, the operation of the loop changer is not required. As the cylinder is opened step by step, the inactive needles in the two sections of the cylinder are alternately raised into active position. As each one comes into active position 50 it takes the yarn when it reaches the yarn feeder and starts a new loop which is the beginning of an additional wale in the fabric.

For the stitching movement of the needles, separate cam blocks may be provided for the 55 needles of the long cylinder and the needles of the short cylinder. A cam block 240 is shown in Figure 1 in position to be engaged by the butt 90 of the needles in the long cylinder. This block is preferably mounted to slide on a stem 241, a 60 spring 242 being employed to hold the block yieldingly in its extended position toward the needles. A block 245 is in like manner yieldingly mounted adjacent to the short cylinder on a stem 246, a 65 spring 247 being provided to press the block toward the cylinder. Thus as the cylinder is moved on its hinge, the block will yield to such motion. It is desirable that the block be held out of contact with the cylinder itself. To this end I may provide a guide or cam ring 250 fixed to the short 70 cylinder. Against a face of this ring the block 245 may bear, a set screw 251 being provided if desired to furnish an adjustable point of contact. As the cylinder revolves, the ring 250 revolves with it and the set screw 251 or other equivalent 75

bearing member rides on a surface of the ring thus holding the block properly spaced from the face of the short cylinder so that the needles of this cylinder engage properly in the cam slot of the block. One or more yarn feeders 260 of conventional type may be mounted on the bracket 233 as shown in Figure 1, these yarn feeders being controlled by any suitable mechanism known in the art but not illustrated on the drawings. A latch ring 265 may also be provided to open the latches of the needles when they are raised for stitching. This latch ring is preferably of a size and shape to operate on the needles when the cylinder is fully expanded. When the cylinder is contracted, it is evident that the latch ring may not be operative as to needles in a portion of the short cylinder. To overcome this deficiency, I may provide a latch opening finger 270 having a curved end 271 adapted to enter the hook portions 20 of the needles and swing the latch out and down. The finger 270 is preferably of resilient material so as to yield readily to the eccentricity of the needle cylinder. A guide member 272 may be provided near the active end of the finger to ride 25 on the surface of the needle cylinder and hold the latch engaging end 271 in correct position relative to the needles. A suitable post 275 (Figures 2 and 10) may be provided for the finger 270.

In the operation of the mechanism as a whole, 30 a certain sequence is required in the actuation of the several mechanisms connected with the fashioning of the fabric. For example, in knitting a stocking such as that illustrated in Figure 31, the stocking may be started at its upper end, the cylinder being expanded to its full circumference so that all the needles are active. The circumference of the upper portion of the leg of the stocking may be regulated by automatically adjusting the tension of the yarn on the sizes to 35 40 the loops in a manner well known in the art. Approaching the ankle portion of the stocking, the circumference of the cylinder may be decreased step by step by the mechanism hereinbefore described. Prior to each adjusting movement of 45 the short cylinder to decrease the circumference of the whole cylinder, one of the sinkers 185 must be moved into inoperative position, and one of the needles in the overlapping portions of the cylinder members must be lowered out of action. To this 50 end the arms 204 and 142 on the post 83 are automatically projected toward the cylinder so as to engage the lower edge of the cam 200 and the edge of the cam 140 as these cams swing past the post 83 with the revolutions of the cylinder. 55 These cam members are thus tilted by engagement with the respective arms, the tilting of the cam member 200 resulting in the movement of one of the sinkers 185 down into its inoperative position so that the overlapped portion 181 of the 60 sinker retaining ring can move under the overlapping portion of the sinker retaining ring 166 for the distance of one needle space. Actuation of the cam 140 results in the raising of one of the needles 47 to a position in which its loop 65 is taken by the loop changer, as hereinbefore described, this being lowered instantly by the lowering of the needle to an inoperative position. The cylinder is now ready for a step of closing movement. This takes place when the star wheel 70 75 75 is passing the post 80 on which the arm 76 has been projected into the path of the star wheel by actuation of the cam slide 82. As hereinbefore explained, the cam 178 for the lugs on the sinkers is so placed that the sinkers are all retracted outwardly as they pass the post 80, a

cam 178 being of sufficient length to ensure that all the sinkers in the overlapping portion of the sinker retaining ring will be simultaneously re-traced at the moment when the cylinder is being closed or opened. Thus when the star wheel 75 5 engages the arm 76 or 77, the overlapping portions of the cylinders are entirely clear. When the cylinder in continuing its revolution moves the needle adjacent to the loop changer around engagement with the stitching cam, the loop 10 which is carried by the loop changer is then taken by the needle, as hereinbefore described, the loop changer then being retracted and the stitching continuing as before with one less needle in the 15 series.

It is to be understood that the description of mechanism embodying the invention and the illustration thereof on the drawings is not by way of limitation but may be modified and changed with the scope of the invention as defined in the 20 following claims.

I claim:

1. In a circular knitting machine, a needle cylinder composed of two parts hinged together and adapted to overlap, and means for relatively adjusting said parts to alter the effective circumference of said cylinder.
2. In a circular knitting machine, a needle cylinder composed of two parts relatively adjustable to vary the effective circumference of the cylinder without interrupting the continuity thereof, and means for relatively adjusting said parts while the machine is in operation.
3. In a circular knitting machine, a needle cylinder having a variable effective circumference, 35 means for varying said circumference without interrupting the continuity thereof, and means for moving needles carried by said cylinder singly into or out of operative position according to the direction of adjustment of said circumference. 40
4. In a circular knitting machine, a needle cylinder comprising two overlapping portions relatively adjustable to alter the effective circumference of the cylinder without interrupting the continuity thereof, means for adjusting said 45 portions, and needles carried by said portions at the overlap movable singly into and out of operative position.
5. In a circular knitting machine, a needle cylinder comprising a semicylindrical member and 50 a semi-conical member hinged together and relatively adjustable to cause portions of said members remote from the hinge to overlap, needles carried by said members with their upper ends arranged in an approximate circle. 55
6. In a circular knitting machine, a needle cylinder comprising a plurality of needle-holding members, a set of needles supported by said members with their tops substantially uniformly spaced apart in a complete approximate circle, 60 and means including said members for changing the circumference of said circle and the corresponding number of active needles therein without interrupting the continuity of said circle.
7. In a machine for knitting tubular fabric, 65 a needle cylinder having a plurality of members relatively movable to alter the circumference of the cylinder by successive steps without interrupting the continuity of said circumference, and means for moving needles into and out of operative position in alternate members when the circumference of the cylinder is changed by successive steps.
8. In a circular knitting machine, a needle cylinder of variable effective circumference, a 75

- sinker-retaining ring having overlapping end portions, sinkers on the overlapping portion of said ring and sinkers on the overlapped portion of the ring movable to inoperative position below the level of the overlapping ring portion, and means for moving the sinkers in the overlapped ring portion into and out of operative position.
9. In a circular knitting machine, a needle cylinder of variable effective circumference, a circular series of needles carried by said cylinder, means for moving certain of said needles into and out of operative position in accordance with variations of the circumference of said cylinder, a circular series of sinkers associated with said needles and means for moving some of said sinkers into position under adjacent sinkers when the circumference of said cylinder is reduced.
10. In a circular knitting machine, a needle cylinder comprising a long member and a short member hinged to each other, the long member being semicylindrical in shape and having a series of needles arranged with their tops in a semicircle, the short member having a wall sloping downwardly and outwardly, and adapted to overlap the long member, said short member having a series of needles with their tops in an approximate semicircle completing a circle with the tops of the needles of the long member, means for effecting a step-by-step variation of the amount of overlap between the members, and means for moving successive needles in the overlapping portions into or out of operative position according to the direction of variation of the overlap.
11. In a circular knitting machine, a needle cylinder comprising two members hinged together and relatively movable to alter the effective circumference of said cylinder, said members having portions adapted to overlap when the circumference of the cylinder is reduced, a sinker retaining ring adjacent to the upper end of said cylinder, said ring comprising a plurality of members relatively movable with said cylinder members and adapted to overlap each other.
12. In a circular knitting machine, a sinker retaining ring comprising two relatively adjustable semicircular members adapted to overlap, a circular series of sinkers radially slideable in said ring, and means for moving the sinkers in the overlapped portion into and out of operative position.
13. In a circular knitting machine, a needle cylinder comprising two relatively adjustable members hinged to each other and having portions remote from the hinge adapted to overlap, a sinker retaining ring comprising two separate members relatively adjustable with said cylinder members and having portions adapted to overlap, a circular series of needles carried by said cylinder, a circular series of sinkers carried by said ring, means for moving a needle and a sinker adjacent thereto out of operative position, and means for thereafter relatively adjusting said cylinder members and ring members to decrease the effective circumferences thereof by distances equivalent respectively to the spacing between successive needles and between successive sinkers.
14. In a circular knitting machine, a rotatable needle cylinder consisting of two members hinged to each other and capable of overlapping to vary the effective circumference of the cylinder, means for rotating said cylinder on its axis, mechanism carried by said cylinder and actuatable to vary the effective circumference thereof, a normally stationary member engageable by said mechanism by rotative movement of said cylinder to actuate said mechanism for step-by-step variation of the circumference of the cylinder.
15. In a circular knitting machine, a rotatable needle cylinder consisting of two members hinged to each other and capable of overlapping to vary the effective circumference of the cylinder, a circular series of needles carried by said cylinder, sinkers associated with said needles, mechanism carried by said cylinder and actuatable to vary the circumference of the cylinder, mechanism carried by said cylinder and actuatable to move certain of said needles into and out of operative position, mechanism carried by said cylinder and actuatable to move certain of said sinkers into and out of operative position, and normally stationary means engageable by the several said mechanisms in their motion with the cylinder to vary the circumference of the cylinder, and move needles and sinkers into and out of operative position.
16. In a circular knitting machine, a needle cylinder comprising two relatively adjustable needle-carrying members having portions adapted to overlap, needles carried by said members with substantially uniform spacing in a circular series, means for raising one of said needles at the overlap to a position for the removal of its loop and to lower said needle to inoperative position, means for transferring the loop from said one needle to an adjacent needle, and means for adjusting the circumference of said members to restore the substantially uniform spacing of the remaining active needles.
17. In a circular knitting machine, a needle cylinder, a circular series of needles in said cylinder, a loop-shifting element within the circle of needles, means for projecting said element radially to take the loop of a needle, means for lowering said needle to cast off its loop, means for shifting said element laterally to the next adjacent needle in said series, means for raising said next adjacent needle to take the loop on said element, and means for withdrawing said element from said loop.
18. In a circular knitting machine, a rotatable needle cylinder, needles in said cylinder, and mechanism actuatable to lower certain of said needles out of action, said mechanism being revolvable with said cylinder about the axis thereof and movable from needle to needle for lowering successive needles.
19. In a circular knitting machine, a rotatable needle cylinder, needles in said cylinder, mechanism actuatable to lower certain of said needles one by one out of action, other mechanism actuatable to raise lowered needles into action, said mechanisms being revolvable with the cylinder about its axis and being movable from needle to needle for actuation of successive needles, and means for selectively actuating said mechanisms.
20. In a circular knitting machine, a split needle cylinder having overlapping portions, a set of needles supported by said portions with their tops substantially uniformly spaced apart in a complete approximate circle, and means for varying the extent of overlap, whereby the effective circumference of the cylinder is varied without interrupting the continuity thereof.

EDGAR J. MARTEL.
